UNITED STATES PATENT OFFICE

GEORGE AINSLIE, OF PORTLAND, OREGON

SUTURING INSTRUMENT

Application filed January 13, 1930. Serial No. 420,429.

My invention relates to suturing instruments and the like.

In a surgical operation, the suturing of the resulting cavity, such as the tonsular fossa resulting from a tonsil operation, is at present a difficult and tedious process particularly so because the cavity is in a more or less inaccessible place.

Elaborate sets of needles of various shapes are required, and the needle with which the suture is to be placed is held by a pair of forceps, and auxiliary instruments are used for holding the bleeding point and directing the needle, which is awkward and requires the use of both hands. Further, the needle must often be pushed through the flesh at an angle to the holding forceps, so that it is frequently misdirected and the placing of the suture must be started over again. Also, the needle is liable to slip out of the holding forceps and be lost in the flesh, in which case, considerable time is consumed in searching for the lost needle, to say nothing of the effect on the patient.

As a result, while every cavity should, in general, be sutured, it is not always done, unless there is an immediate need, as for instance, if the cavity is bleeding, or the cavity for other reasons must be closed at once.

Therefore, the object of my invention is to provide a simple surgical instrument adapted to be operated by one hand to place a suture with certainty in any cavity which can be seen, without the use of auxiliary instruments, such as hooks, spatulas for counter pressure for the needle, and the like.

A further object of my invention is to provide a suturing instrument to which the needle is positively connected, and by which it is positively operated so that the needle can not, under any circumstances, be misdirected, or fall out of the instrument and be lost in the flesh.

A further object of my invention is to provide a suturing instrument, the needle of which is adapted to first pierce the flesh on each side of the bleeding point, thus drawing the flesh more or less together, and then to engage and draw the suture through the flesh as the needle is retracted, thus prevent-

ing the possibility of the suture falling off the needle as it pierces the flesh.

I attain my objects in a suturing instrument comprising substantially a casing provided with projecting, arcuate, a distal and proximal arms arranged to provide a flesh-admitting cavity between and forming a guide flange about said cavity, a curved suture needle slidably mounted on said guide flange within said casing. The distal arm of the casing provided at its extremity with means for holding a suture, the needle provided with means adjacent its point for engaging the suture, and simple operating means for moving the needle about said guide flange, whereby when said needle is projected from the proximal arm of the casing and through the flesh on each side the cavity to be sutured, the needle will enter said distal arm and engage the suture, and when the needle is retracted, the suture will be disengaged from said proximal arm and drawn through the sides of the cavity, thus placing the suture surely and quickly.

These and other incidental features of my invention, the details of construction, and mode of operation are hereinafter more fully described with reference to the accompanying drawings.

In the drawings:

Fig. 1 shows a side elevation of my suturing instrument;

Fig. 2 shows a front elevation of my instrument taken in the direction of the arrow 2 in Fig. 1;

Fig. 3 shows a view of my instrument taken similarly to Fig. 1, except the handle elements are shown partly in section;

Fig. 4 shows the two complementary parts of the casing containing the suture needle removed from the rest of the instrument;

Fig. 5 shows an enlarged, central, longitudinal section of my instrument taken similarly to Fig. 1, with one of the needle casing halves removed, and illustrates the details of construction of the suture needle and operating means;

Fig. 6 shows a fragmentary view of the needle casing and suture needle similarly to

Fig. 5, except that the needle is in its projected position;

Fig. 7 shows a view similar to Fig. 6 but illustrates the needle in the operation of being retracted and drawing the suture after it;

Fig. 8 shows, more or less diagrammatically, how the suture disengages itself from the instrument after it is placed;

Fig. 8a shows a top end view of the instrument as shown in Fig. 7 and illustrates how the suture needle engages the suture;

Fig. 9 shows a side elevation of the suture needle removed from the casing;

Fig. 10 shows a large scale section taken on the line 10—10 of Fig. 9;

Fig. 11 shows a side elevation of my suture instrument embodying a modification;

Fig. 12 shows an enlarged longitudinal section taken through Fig. 11 and illustrates the said modification, consisting in providing flexible cable element for operating the suture needle;

Fig. 13 shows further, similarly to Fig. 12, said modification of my instrument, the suture needle being shown in its projected position;

Fig. 14 shows a side elevation of a further modification of my suturing instrument;

Fig. 15 shows a fragmentary, and enlarged, central, longitudinal section of Fig. 14 and illustrates the means provided for operating the suture needle;

Fig. 16 shows a view similar to Fig. 15, and illustrates the suture needle in its projected position;

Fig. 17 shows a side elevation of the suture needle removed from the instrument;

Fig. 18 shows a section taken on the line 18—18 of Fig. 15; and

Fig. 19 shows a section taken on the line 19—19 of Fig. 15.

Referring now to Figures 1 to 10, my suturing instrument comprises a needle casing *a*, formed in complementary halves *a'*, *a''* and having opposite opposed arcuate arms *b*, *c*, forming a flesh admitting cavity between, and described for convenience as the distal and proximal arms, respectively. The casing halves are held together by a screw *d*, and the shank of the casing is threaded as at *e* and is adapted to be secured to the end of a tubular member *f* by means of an internally threaded collar *g*.

A curved suture needle *h* is provided with in the said needle casing *a*, with the point *h'* arranged so as to project from the said proximal arm *c*. The other or butt end *h''* of the needle is pivotally connected to a curved arm *j*. The other end of the curved arm is connected to a flexible wire rod *k* by a ball *l* seated in a socket *l'*, having an entrance slot *l''*. The rod *k* is arranged in the said tubular element to the end of which a handle member *m*, having a finger ring *m'* is secured by means of a set screw *m''*.

A slide *p* is mounted on the said handle and provided with finger rings *p'* at each side. A flat spring *q* is provided in the slide and bears against the handle to prevent free movement of the slide on the handle. The end of the rod *k*, which extends through the tubular member *f*, is secured to the slide *p* and enlarged to form a shoulder *k'*.

By this construction, as the slide *p* is moved back and forth on the handle *m*, the needle *h* will be reciprocated in the casing *a* as illustrated in Figs. 5, 6, 7, and the shoulder *k'* will serve as a stop to the inward movement of the rod *k* in order to prevent the possible buckling of the rod in the tubular member *f*.

The needle *h* is provided adjacent its point with a suture engaging notch 2 and the distal arm *b* of the casing is provided with a suture holding notch 3, see Fig. 8a, having an entrance slot 3a extending to the end of the said distal arm. A spring clip 4 is provided on the handle *m* for releasably holding the free ends of a thread or suture, as *x*.

The mode of operation of my suture instrument is as follows: Assuming that the bleeding point of a tonsular fossa is to be sutured, as illustrated in Figs. 5, 6, 7, the suture is first placed in the notch 3 in the distal arm at about its middle point thus forming a loop, and the ends *x'* of the suture are releasably secured under the spring clip 4 on the handle for convenience in holding the suture in place on the instrument.

Then, as illustrated in Fig. 5, the instrument is held in one hand by the finger rings *m'* and *p'* and the arms *b*, *c* of the casing *a* are positioned over the sides of the tonsular fossa, with the needle *h* in the retracted position. The wire rod *k* is then drawn outwardly from the casing *a* by the finger rings *p'* which projects the needle *h* from the proximal arm and pierces the flesh on each side of the cavity, at the same time drawing the sides of the cavity more or less closely together. As the point *h'* of the needle enters the distal arm of the casing, its notch 2 engages the suture, Figs. 6 and 8a, and then, as shown in Fig. 7, the wire rod *k* is operated to move inwardly toward the casing *a* and retract the needle *h*, which draws the loop *x''* of the suture from the distal arm and through the flesh, thus the suture is placed.

As soon as the ends *x'* of the suture are drawn from under the spring clip 4 on the handle, the suture becomes loose and slips from the end of the distal arm, see Fig. 8, through the entrance slot 3a. Similarly the suture releases itself from the notch 2 in the needle. The suture is then drawn together and tied in the usual manner.

Referring now to Figs. 11 to 13 inclusive, I have substituted a flexible cable 10 for connecting the wire rod 11 to the butt end of the suture needle 12, the latter having a groove

12a in its external periphery to accommodate the adjacent portion of the cable 10. The needle casing 14 is the same as previously described except that this modification permits the outer circumference of the distal arm 15 to be annular in form, since no space need be provided within the casing to accommodate the movement of the curve arm *j*, shown in Figs. 1 to 10. By this construction, the 10 arms of the casing may be more conveniently positioned for the placing of the suture within a limited working space.

Figs. 14 to 19 inclusive show a still further modification of my invention, having the advantage of the external circumference of the distal arm 20, being annular in form but at the same time providing a positive connection between the suture needle 21, and the wire rod 22. The needle casing 23 is provided 20 with a chord-like inner wall 24, providing space within the casing for the movement of a straight connecting arm 25, pivotally connected with the butt end of the suture needle 21, as at 21a, which is similar to the suture 25 needles heretofore described except that the needle is provided with an elongate, central slot 28 in which the straight arm 25 is arranged, and in which it operates. The other end of the straight arm 25 is secured to a 30 separable ball and socket joint 26, as at 21b, carried by the said wire rod 22.

The modification of my instrument, illustrated in Figs. 11 to 13, is especially adapted for the construction of very small instruments where the space within which the suture is to be placed may be limited and the cavity small, such as in a rectal operation, and the modification illustrated in Figs. 14 to 40 19 provides a large size instrument, where large cavities are to be sutured and consequently a more strongly constructed instrument is required.

I claim:

1. In a suturing instrument, a casing provided with projecting, arcuate, distal and proximal arms arranged to provide a flesh-admitting cavity between them, a curved suture needle slidably mounted in said casing, the distal arm provided at its extremity with means for holding a suture, the needle provided with means adjacent its point for engaging the suture, a member located in said casing and pivotally connected to said needle, a hollow handle provided with a finger hold secured to said casing, a rod slidably within said handle and detachably connected to said member and a slide mounted on the handle, said slide provided with a finger hold, and the said rod being connected to said slide.

2. In a suturing instrument, a casing having a neck and provided with projecting, arcuate, distal and proximal arms arranged to provide a flesh-admitting cavity between them, a curved suture needle slidably mount-

ed in said casing, the distal arm provided at its extremity with a suture holding notch, the needle provided with a notch adjacent its point for engaging the suture, a member located in said casing and pivotally connected to said needle, a hollow handle provided with a finger hold secured to the neck of said casing, a rod slidably within said handle and detachably connected to said member and a slide mounted on the handle, said slide provided with a finger hold, and the said rod being connected to said slide.

3. In a suturing instrument, a casing consisting of a divided head having a neck and provided with projecting, arcuate, distal and proximal arms arranged to provide a flesh-admitting cavity between them, a curved suture needle slidably mounted in said casing, the distal arm provided at its extremity with a suture holding notch, the needle provided with a notch adjacent its point for engaging the suture, a curved member located in said head and pivotally connected to said needle, a hollow handle provided with a finger hold secured to the neck of said casing, a rod slidably within said handle and detachably connected to said member and a slide mounted on the handle, said slide provided with a finger hold, and the said rod being connected to said slide.

4. In a suturing instrument, a casing consisting of a divided head having a neck and provided with projecting, arcuate, distal and proximal arms arranged to provide a flesh-admitting cavity between them, a guide flange circumscribing said cavity, a curved suture needle slidably mounted on said guide flange within said casing, the distal arm provided at its extremity with a suture holding notch, the needle provided with a notch adjacent its point for engaging the suture, a hollow handle provided with a finger hold secured to the neck of said casing, a rod slidably within said handle and detachably connected to said member, a member located in said head, a ball and socket separable joint connecting said rod with said member and a slide mounted on the handle, said slide provided with a finger hold, and the said rod being connected to said slide.

5. In a suturing instrument, a casing consisting of a divided head having a neck and provided with projecting, arcuate, distal and proximal arms arranged to provide a flesh-admitting cavity between them, a guide flange circumscribing said cavity, a curved suture needle slidably mounted on said guide flange within said casing, the distal arm provided at its extremity with a suture holding notch, the needle provided with a notch adjacent its point for engaging the suture, a hollow handle provided with a finger hold secured to the neck of said casing, a rod slidably within said handle and detachably con-

nected to said member, a member located in said head, a ball and socket separable joint connecting said rod with said member and a slide mounted on the handle, said slide provided with a finger hold, and the said rod being connected to said slide.

6. In a suturing instrument, a casing provided with projecting, arcuate, distal and proximal arms arranged to provide a flesh-

10 admitting cavity between them, a guide flange circumscribing said cavity, a curved suture needle slidably mounted in said casing, the distal arm provided at its extremity with a suture-holding notch, the needle pro-

15 vided with a notch adjacent its point for engaging the suture, a member located in said casing and pivotally connected to said needle, a hollow handle provided with a finger hold secured to said casing, a rod slidably within

20 said handle and detachably connected to said member, a slide mounted on the handle, said slide provided with a finger hold, and the said rod being connected to said slide.

7. In a suturing instrument comprising, a 25 casing provided with projecting, arcuate, distal and proximal arms arranged to provide a flesh-admitting cavity between them, a guide flange circumscribing said cavity, a curved suture needle slidably mounted on

30 said guide flange within said casing, the distal arm provided at its extremity with a suture holding notch, the needle provided with a notch adjacent its point for engaging the suture, a hollow handle provided with

35 a finger hold secured to said casing, a flexible rod slidably within said handle and detachably connected to said member, a curved member located in said casing, a ball and socket separable joint connecting said rod

40 with said member and a slide mounted on the handle, said slide provided with a finger hold, and the said rod being connected to said slide.

8. In a suturing instrument, a casing pro- 45 vided with projecting arcuate distal and proximal arms arranged to provide a flesh admitting space between them, the distal arm provided at its extremity with means for removably holding a suture, a curved suture-

50 needle slidably carried by said casing, and arranged to be projected from said proximal arm, the needle provided adjacent its point with means for engaging the suture, operable means for moving said needle in said casing,

55 whereby when the needle is projected from said proximal arm and through the flesh, the needle will engage the suture held by the distal arm, and upon retraction of the needle the suture will be disengaged from the distal arm.

9. In a suturing instrument, a hollow cas- 60 ing including arcuate distal and proximal arms arranged to provide a flesh-admitting

65 space between them, the distal arm provided at its extremity with means for removably

holding a suture, a curved suture-needle slidably carried by said casing, the needle provided with means adjacent its point for engaging the suture, a hollow handle for said casing, a rod slidably held by said handle, a detachable articulate connection from said rod to said needle.

10. In a suturing instrument, a casing in- 70 cluding arcuate distal and proximal arms ar-

75 ranged to provide a flesh-admitting space be- 75

80 tween them, the distal arm provided at its extremity with means for removably holding a suture, said casing provided with a handle, the lower end of the latter provided with a finger hold, a curved suture-needle slidably

85 carried by said casing, the needle provided with means adjacent its point for engaging the suture, a hollow handle for said casing, a rod slidably held by said handle, a detach- 85

90 able articulate connection from said rod to said needle, a slide mounted on the handle to which slide said rod is connected, said slide provided with oppositely disposed finger holds transversely of the axis of said handle.
